CLAIM

The ornamental design for a smartphone with slidable display, as shown and described.

DESCRIPTION

FIG. 1 is a front view of a smartphone with slidable display showing our new design shown in a first state environment;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is another front view thereof, shown in an alternate position first state environment;

FIG. 8 is a front view of a smartphone with slidable display showing our new design shown in a second state environment;

FIG. 9 is a rear view thereof;

FIG. 10 is a left side view thereof;

FIG. 11 is a right side view thereof;

FIG. 12 is a top view thereof;

FIG. 13 is a bottom view thereof;

FIG. 14 is another front view thereof, shown in a first position second state environment; and,

FIG. 15 is yet another front view thereof, shown in a second position second state environment.

The dashed broken lines are directed to environment and are for illustrative purposes only; the broken lines form no part of the claimed design.

1 Claim, 11 Drawing Sheets
